UNITED STATES PATENT OFFICE.

VICTOR D. LESPINASSE, OF CHICAGO, ILLINOIS.

CAPONIZING TOOL.

Application filed January 22, 1923. Serial No. 614,155.

To all whom it may concern:

Be it known that I, VICTOR D. LESPINASSE, a citizen of the United States, and resident of Chicago, in the county of Cook and State 5 of Illinois, have invented a certain new and useful Improvement in Caponizing Tools, of which the following is a full, clear, concise, and exact description, reference being had to the accompanying drawings, forming a part 10 of this specification.

This invention relates to caponizing tools of the character employed to seize and raise the testicle of a bird, and is designed as an improvement on the device disclosed in applicant's prior Patent No. 1,451,398, issued 15 April 10, 1923.

The object of the invention is to provide an instrument of this character, which may be easily placed in a position to seize the 20 structures and tissues attaching the testicle to the bird's body and not injure either the large blood vessels lying immediately beneath the testicle or the testicle itself, and which may be manipulated to grasp the 25 small blood vessels and tissues between the testicle and the bird's body during the raising operation in order to take the strain from off the testicle, thus insuring the removal of all the testicle and preventing the 30 rupture thereof during the removing process.

One of the features of the invention is the provision of means whereby the substantially parallel portions forming the slot at the working extremity of the device may be moved forcibly toward each other during the 35 raising process.

Another feature resides in the limiting means associated with the part forming the slot for normally limiting the distance these 40 parts may be separated, by the spring action of the tweezer-like handle, but permitting said parts to be further separated if desired for cleaning or other purposes.

A still further feature resides in so arranging the limiting means referred to above that it acts to normally close the outer 45 end of the slot, thus preventing the escape from the slot of the blood vessels and tissues attaching the testicle to the bird's body.

Other features and advantages will appear 50 from time to time as the description of the invention progresses.

It is believed that the invention will be 55 best understood by first describing the structure of the apparatus in connection with the accompanying drawings, and then describ-

ing the manner in which the instrument is intended to be employed.

Referring now to the drawings,

Figure 1 is an edge view showing the instrument in substantially its actual size; 60

Figure 2 is a view taken at right angles to Figure 1;

Figure 3 is a view looking at the working end of the device and shows the parts enlarged, and in separated position; 65

Figure 4 is a view similar to Figure 3, but shows the parts forming the slot in normal operative position;

Figure 5 is another view similar to Figure 4, but shows the members forming the slot forced together by pressure on the tweezer-like handle. 70

Figure 6 shows a cross-section through the fingers forming the slot of a modified form 75 of the device;

Figure 7 is a view similar to Figure 6, but illustrating another modification;

Figure 8 shows still another modification 80 of the fingers;

Figures 9 and 10 show still other modifications and illustrate the manner of employing the instrument in operation; and

Figure 11 is a perspective view showing 85 schematically a portion of the bird and the manner of employing the instrument.

In the drawings, in which like reference characters indicate like parts in the several views, 10 and 11 indicate the spring-like or flexible members which form the handle of 90 the instrument. The parts 10 and 11 are rigidly secured together at one end in any desired manner, and diverge slightly from each other toward the opposite end. The set in the parts 10 and 11 is such as to tend to 95 move the free ends thereof from each other. The handle comprising the parts 10 and 11 may, if desired, be in all respects similar to that of the ordinary tweezers.

The part 10 at the lower end thereof, as 100 seen in Figure 1, is provided with the outwardly and then inwardly curved portion 12, and the part 11 is provided with the similar outwardly and then inwardly curved portion 13. The parts 12 and 13 are opposed to each other, thus forming an eye or loop 105 14 therebetween, through which the testicle of the bird is passed in the manipulation of the instrument.

The member 12 terminates in the laterally 110 directed finger 15 and the member 13 in a similar finger 16. When the device is in

operative position, the fingers 15 and 16 are held slightly spaced apart as shown in Figure 4, and extend in substantially parallel relation, thus forming a slot 17 therebetween. The slot 17 will preferably, but not necessarily, taper slightly from the open end thereof toward the free end or point of the device.

The finger 16 is provided at its end with a laterally and rearwardly extending portion 18, which is adapted to overlie the beveled portion 19 at the end of the finger 15. The rebent or hook-like portion 18 acts to normally limit the separation of the fingers 15 and 16. The part 18 also acts to close the end of the slot 17. When, however, it is desired to separate the parts 15 and 16 for cleaning or any other purpose, the parts 12 and 13 are moved slightly laterally with respect to each other, thus freeing the part 19 from the part 18 and permitting the fingers to assume the position indicated in Figure 3.

In the preferred embodiment of the invention disclosed in the drawings, the parts 15 and 16 extend laterally substantially at right angles to the plane of the parts 12 and 13. It is not necessary, however, that the fingers extend at right angles to the parts 12 and 13 and in certain cases other angular arrangements may be preferred. The fingers 15 and 16, as shown in Figures 1 to 5 of the drawings, are preferably slightly oblong in cross-section. However, the cross-sections of these fingers may be varied.

In Figure 6, a modified form of the fingers is shown. As shown in this figure, the fingers 20 and 21 are provided with the cutting edges 22 and 23, which lie next to the bird's body when the tool is applied, and which are adapted to be brought forcibly into engagement when pressure is applied to the sides of the handle member 10 and 11.

In Figure 7, a further modified form of the fingers is shown. In this construction, the fingers are substantially L-shaped in cross-section to insure a substantial space between the upper portions of the fingers when the tissues and small blood vessels attaching the testicle to the bird's body are clamped between surfaces 24 and 25. This construction largely eliminates the possibility of rupture of the testicle when the small blood vessels and tissues are grasped by the abutting edges of the fingers, as the upwardly extending portions 26 of the fingers act to remove the testicle from the path of the abutting faces of the device.

In the form of device shown in Figure 8, the fingers have in general the form as the modification shown in Figure 7, but, in addition, are provided with cutting edges 27-27 similar to the edges 22 and 23 of the form shown in Figure 6.

In the modification of Figure 9, the edge

31 slidably engages the inclined surface 32 when pressure is brought to bear on the sides of the handle, thus acting to sever the tissues and small blood vessels. At the same time the abutting surfaces 33 and 34 grasp the severed tissues and blood vessels and hold them securely until pressure on the sides of the handle is released.

The arrangement of Figure 10 is similar in operation to that of Figure 9, except that the edge 35 co-operates with the shoulder 36 to produce a more definite shearing action.

The method of employing the instrument will now be described. The bird being bound and held with one side uppermost, an incision is made between the last two rear ribs. The edges of the cut are then spread and maintained in spread relation by means of the spreader indicated at 28 in Figure 11. The underlying tissues are then perforated and access to the testicle 29 obtained in the usual manner. The testicle being now exposed, the instrument is held lightly in the hand as shown in Figure 1, and is placed in the cut with the loop portion preferably directed toward the head of the bird. The parts 15 and 16 being placed in contact with the bird's body, the instrument is drawn gently toward the tail of the bird, causing the testicle to pass through the eye 14. This operation should be performed very easily, and if any force appears to be necessary, the instrument should be shifted slightly and the slotted portion preferably pointed in a slightly different direction. In certain instances, it may be preferred to pass the instrument from the tail toward the head of the bird, but the process will be performed in exactly the same manner, regardless of from which direction the instrument is applied. However, the slot of the instrument should usually occupy a position from head to tail of, or from tail to head of the bird being operated upon.

After the testicle has passed through the eye 14, the instrument is moved still further forward, causing the blood vessels and tissues which attach the testicle to the bird to pass into the slot 17. The loop or hook 18 at the end of the finger 16 prevents such blood vessels and tissues from passing beyond the slot.

It is now necessary to raise the testicle away from the bird's body. If the instrument be drawn upwardly without bringing the fingers 15 and 16 together, the testicle will be brought forcibly into contact with the upper edges of the fingers 15 and 16 with the attendant danger of the testicle being ruptured and part thereof escaping, and not being removed. The present device is so designed that the blood vessels and tissue may be forcibly grasped between the parts 15 and 16 during the drawing or raising

process, thus taking the strain from off the testicle and reducing to the minimum the danger of rupturing it. During the drawing process, the parts 10 and 11 of the handle 5 are forced toward each other, thus causing the blood vessels to be securely gripped between the fingers 15 and 16. If desired, the instrument may be rotated during or after the drawing process, thus acting to twist the 10 blood vessels into a cord 30 in the customary manner, the blood vessels afterwards being severed by means of a pair of scissors.

In the form of the device shown in Figure 6, when pressure is brought to bear on the 15 flexible members 10 and 11 of the handle, the edges 22 and 23 are caused to firmly grip and crush the blood vessels. With this form of the device, the blood vessels and tissues attaching the testicle to the bird may often 20 be severed directly by the edges 22 and 23, thus making the use of scissors unnecessary.

In the devices shown in Figures 9 and 10, movement of the fingers toward each other 25 serve successively to shear or sever the cord of tissues and blood vessels connecting the testicle with the bird's body, and then firmly to clamp and hold that portion of the cord adhering to the testicle.

While applicant has disclosed the preferred embodiment of his invention, it is to 30 be understood that many modifications thereof are contemplated. For instance, the fingers forming the slot may extend at other angles rather than at right angles to 35 the plane of the members 12 and 13. Also the handle or supporting portion of the device may be of scissors-like formation, rather than tweezers-like. The fundamental requisite of the invention is the provision of a 40 pair of supporting arms, the free ends of which may be moved slightly toward and from each other, and the provision at the ends of these arms of oppositely curved portions which terminate in substantially parallelly extending fingers forming a slot therebetween. In view of the many modifications 45 which may be made in applicant's invention without departing from the spirit thereof, the invention should be limited merely by 50 the scope of the appended claims.

Having thus described my invention, what I claim is new and desire to secure by Letters Patent of the United States is.

1. In a caponizing instrument, a pair of 55 members having adjacent ends which are arranged to be moved toward and away from each other, said ends being normally spaced slightly apart and provided with inwardly curved portions, substantially parallel 60 separate fingers in which said curved portions respectively terminate, and means carried by said fingers for normally limiting the distance which said fingers will separate, said means being arranged to normally close 65 one end of the slot between said fingers.

2. In a caponizing instrument, a pair of members having adjacent ends which are spaced slightly apart, and capable of movement toward and from each other, said ends being provided with outwardly and then inwardly curved portions forming an eye therebetween, substantially parallel fingers in which said curved portions respectively terminate, said fingers normally affording a narrow elongated slot between them, one 70 of said fingers being provided at the end thereof with a rebent portion adapted to engage the end of the other finger to close one end of said slot and limit the distance which said fingers will normally separate. 75

3. In a caponizing instrument, a pair of flexible members secured together at one end, the opposite or free ends of said members being spaced slightly apart and provided with outwardly and then inwardly curved 80 portions forming an eye therebetween, separate substantially parallel fingers in which said curved portions respectively terminate, and means carried by said fingers for normally limiting the distance which said 85 fingers will separate. 90

4. In a caponizing instrument, a pair of flexible members secured together at one end, the opposite or free ends thereof being spaced slightly apart and formed with outwardly and then inwardly curved portions, substantially parallel fingers in which said curved portions respectively terminate, said fingers normally affording a narrow elongated slot between them and a laterally 95 extending portion at the free end of one of said fingers for normally closing one end of the slot between said fingers. 100

5. In a caponizing instrument, a pair of flexible members secured together at one end, the opposite or free ends of said members being spaced slightly apart and provided with outwardly and then inwardly curved portions forming an eye therebetween, laterally extending substantially parallel fingers in which said curved portions respectively terminate, one of said fingers being provided at the end thereof with a rebent portion adapted to engage the end of the other finger. 110

6. In a caponizing instrument, a pair of flexible members secured together at one end, the opposite or free ends of said members being spaced slightly apart, and provided with outwardly and then inwardly curved portions forming an eye therebetween, laterally extending substantially parallel fingers, L-shaped in cross-section, in which said curved portions respectively terminate, one of said fingers being provided at the end thereof with a rebent portion adapted to engage the end of the other finger. 115

7. In a caponizing instrument, a pair of flexible members secured together at one 120 125 130

- end, the opposite or free ends of said members being spaced slightly apart, and provided with outwardly and then inwardly curved portions forming an eye therebetween, laterally extending substantially parallel fingers, L-shaped in cross-section, in which said curved portions respectively terminate, one of said fingers being provided at the end thereof with a rebent portion adapted to engage the end of the other finger, and cutting edges on said fingers adapted to be brought into engagement each with the other.
8. In a caponizing instrument, a pair of flexible members secured together at one end, the opposite or free ends of said members being spaced slightly apart, and provided with outwardly and then inwardly curved portions forming an eye therebetween, laterally extending substantially parallel fingers, L-shaped in cross-section, in which said curved portions respectively terminate, one of said fingers being provided at the end thereof with a rebent portion adapted to engage the end of the other finger, said fingers being provided with shear-
- ing edges and opposed clamping surfaces, said clamping surfaces being adapted firmly to engage and hold the tissue and blood vessels severed from the bird's body by the action of said shearing edges.
9. In a caponizing instrument, a pair of relatively movable arms having angularly extending juxtaposed portions which are adapted to provide between them an open ended slot for the reception of the cord of tissues and blood vessels connecting the testicle with the body of a bird, said arms being spring urged to positions whereby they provide the slot aforesaid but adapted to be manually operated firmly to grasp the cord between the angularly extending portions aforesaid, and means associated with said portions for limiting their movement from each other.
- In witness whereof, I hereunto subscribe my name this 19 day of January, 1923.
